(57) **CLAIM**

The ornamental design for a transparent or translucent photography table, as shown and described.

DESCRIPTION

FIG. 1 is a perspective view of a first embodiment of our new design for a transparent or translucent photography table;

FIG. 2 is a front and back view thereof;

FIG. 3 is a first and second side view thereof;

FIG. 4 is a top view thereof;

FIG. 5 is a bottom view thereof;

FIG. 6 is a perspective view of a second embodiment of our new design for a transparent or translucent photography table;

FIG. 7 is a front and back view thereof;

FIG. 8 is a first and second side view thereof;

FIG. 9 is a top view thereof; and,

FIG. 10 is a bottom view thereof.

The evenly spaced broken lines in the drawings depict environmental subject matter only and form no part of the claimed design. The long-dash to short-dash lines in the above described Figures are boundary lines and form no part of the claimed design.

1 Claim, 10 Drawing Sheets
